UNITED STATES PATENT OFFICE

139,338

DESIGN FOR A DOORKNOB OR THE LIKE

Harry F. George, Chicago, Ill.

Application January 19, 1944, Serial No. 112,271

Term of patent 14 years

(Cl. D50—3)

To all whom it may concern:

Be it known that I, Harry F. George, a citizen of the United States residing at Chicago, in the County of Cook and State of Illinois, have invented a new, original, and ornamental Design or a Doorknob or the like, of which the following is a specification, reference being had to the accompanying drawing, forming a part thereof,

In the drawing:

I claim:

The ornamental design for a doorknob or the like, substantially as shown.

HARRY F. GEORGE,
